UNITED STATES PATENT OFFICE.

HENRY BARDSLEY, OF PROVIDENCE, RHODE ISLAND, ASSIGNOR TO CROMPTON & KNOWLES LOOM WORKS, OF PROVIDENCE, RHODE ISLAND, A CORPORATION OF RHODE ISLAND.

LOOM-SHUTTLE.

SPECIFICATION forming part of Letters Patent No. 691,577, dated January 21, 1902.

Application filed September 25, 1901. Serial No. 76,460. (No model.)

To all whom it may concern:-

Be it known that I, HENRY BARDSLEY, a citizen of the United States, residing at Providence, in the county of Providence, State of Rhode Island, have invented a certain new and useful Improvement in Loom-Shuttles, of which the following is a specification, reference being had therein to the accompanying drawings.

10 The invention relates to the devices which are employed in loom-shuttles for the purpose of ascertaining when the yarn-load which is carried by the working shuttle of a loom has become exhausted or depleted to the predetermined extent and for the further purpose of calling into action instrumentalities for bringing about a prearranged change in the working of the loom.

15 The invention consists in improved devices of the said class and first will be described with reference to the drawings, in which latter is represented an embodiment of the invention, after which the characteristic and essential features of the invention will be particularly pointed out and distinctly defined in the claims at the close of this specification.

20 In the drawings, Figure 1 shows, mainly in plan, part of a loom-shuttle having an embodiment of the invention applied thereto, a portion of the shuttle-body being broken away adjacent the trip. Fig. 2 is a side elevation of the same, one side of the shuttle-body being broken away for part of its length.

25 Having reference to the drawings, I designate the shuttle-body, only a portion thereof being shown.

30 2 is a wound yarn-load in the shape of a cop, which is shown located within the main cavity or the yarn-receiving chamber of the said shuttle-body. I provide the shuttle with a movable follower, making contact with the exterior of the yarn-load and controlled as to its position by the mass of the latter. The follower is maintained in an abnormal position by the said mass so long as the diameter of the portion of the yarn-load against which it bears exceeds the predetermined diameter; but it is permitted to approach its normal position by the diminution of the diameter of

the yarn-load as the depletion of the latter 50 progresses. I provide the shuttle also with a device which for convenience of reference I term a "trip" and which is intended when in its normal position to coact with or control outside instrumentalities for bringing 55 about the desired results in the working of the loom in which a shuttle embodying my invention is employed. Thus, as will be obvious to those who are skilled in the art, the said trip may be utilized to bring about an 60 arrest of the action of the whole or of some part of the loom mechanism or to bring about automatic replenishment of the working weft-supply, all substantially as heretofore proposed in the art. The said outside instrumentalities and the precise manner of the co-operation of the trip therewith are not material to my invention, which resides in the shuttle and its parts, and may be varied in practice. The follower is furnished with an 70 engaging portion or detent, which coacts with the trip and operates to maintain the trip in its abnormal position so long as the diameter of the portion of the yarn-load against which the follower acts exceeds the predetermined 75 minimum. The consumption of the said yarn-load in the process of weaving, and consequent decrease in diameter of the said portion thereof, permits the follower to approach its normal position, and at the predetermined point the detent is disengaged from the trip, allowing the trip to take its normal and operative position. The construction and arrangement of the follower and trip and the manner of combining them with the loom-shuttle may vary in practice. I prefer, in accordance with one portion of my invention, to apply the follower to the receiver or holder for the yarn-load, since thereby greater facility in the use of the invention is secured, 80 and to apply the trip to the shuttle-body in such manner that as the said receiver or holder with a yarn-load upon the same is depressed into the yarn-receiving cavity of the shuttle the detent of the follower will engage 85 with the trip and maintain the latter in its abnormal or inoperative position. More especially in shuttles in which the yarn-loads

are received upon spindles pivotally mounted within the shuttle-bodies in the usual manner I preferably mount the follower upon the spindle, so as to move in unison with the 5 spindle as the latter is raised and lowered, the follower being given also an independent indicating movement relative to the spindle.

The drawings show the shuttle as provided with a shuttle-spindle 3, which is pivoted 10 within the shuttle-body upon a transverse pin 4, as usual in shuttles. The yarn-load 2 is shown applied to the said shuttle-spindle in the form of a cop. The drawings show also the follower at 5, it being pivoted at 6 15 upon the butt of the spindle 3. The pivotal pin at 6 occupies a vertical position, so that the follower 5 is adapted to swing transversely in the shuttle, its feeling end moving transversely toward and from the blade of the 20 spindle. The said feeling end is furnished with a rounded contact portion 51 to bear against the exterior of the cop 2 at the base of the cop. A bent-wire spring 7, attached to the butt-end of the spindle 3 by means of a 25 screw 71, has its free end engaged in a hole in the follower, as shown in Fig. 1, and acts with a tendency to turn said follower upon its pivot 6, so as to press its feeling end inward against the yarn-load.

30 The trip is designated 8 and is shown mounted upon a vertical pivot 81 in a slot 82, formed for its reception in the side of the shuttle-body. The operative end 83 of the said trip is exposed at the said slot in position to coact with the outside instrumentalities, to which reference has been made. The manner of the coaction may vary in practice; but in the present instance the said end 83 is furnished with a tooth or projection (see 35 Fig. 1) to engage with a coöperating trip on the lay of the loom as the shuttle enters the receiving shuttle-box at the end of a flight across the loom. A spring 84 acts upon the trip with a tendency to move it into its normal or operative position, and a pin 85 or 40 equivalent stop limits the movement of the trip under the action of the said spring.

For the purpose of detaining the trip in an abnormal or inoperative position so long as 45 the required volume of yarn is contained within the shuttle the follower 5 is provided, as already referred to, with a detent which is shown at 9 and constituted by a pin movable transversely through a hole formed in the butt-end of the spindle 3, one end thereof being pivotally connected with the corresponding end of the follower 5 and the other end thereof being arranged to engage with 50 the arm 861 on the trip 8. In the retracted or inoperative position of the trip while engaged by the detent 9 its tail 86 makes contact with the adjoining wall of the shuttle-body at one end of slot 82, and thereby the 55 trip is steadied.

In the illustrated embodiment of the invention the follower and its detent in conse-

quence of being mounted upon the shuttle-spindle 3 move in unison with the shuttle-spindle as the latter is raised and lowered. 70 The raising of the shuttle-spindle, therefore, disengages the detent 9 from the trip. The proper reengagement of the said parts after the shuttle-spindle has been lowered again may be arranged to be effected manually, if 75 desired; but preferably I arrange to cause the same to be effected automatically and without manual intervention by providing one of the interengaging parts with a curved or cam-shaped guiding-wing, which receives 80 the contact of the other as the spindle is lowered and retracts the trip. Herein the said wing is shown at 87, formed upon the trip and extending upwardly therefrom to receive on its acting face the contact of the correspond- 85 ing end of the detent 9 during the lowering of the shuttle-spindle.

It will be perceived that by the action of spring 7 the contacting portion 51 of the follower 5 is held pressed against the exterior 90 of the base of the yarn-load 2, and when in the course of the weaving the said base begins to decrease in diameter the follower is allowed to turn correspondingly until the required reduction in the diameter of said base 95 has taken place, at which latter time the detent 9 will become fully disengaged from the trip, leaving the latter free to assume its normal or operative position. It is desirable that convenient means should be provided 100 for enabling the time of the release of the trip to be regulated, so that differences in the sizes of yarns used at different times may be accommodated and whereby the said release may be caused to occur while the desired 105 length of weft still remains unwound in the yarn-load. To this end I provide the follower 5 with an adjusting-screw 52, acting in connection with the contact portion 51, which latter is constituted of an elastic blade or 110 strip attached by one extremity thereof to the follower.

I claim as my invention—

1. In a loom-shuttle, in combination, a movable follower acting against the exterior of 115 the wound yarn-load carried by the shuttle and provided with a detent, and a trip adapted in its normal position to control the action of outside instrumentalities, and held by such detent in an abnormal position until its release is permitted by depletion of the said 120 yarn-load to the predetermined extent, substantially as described.

2. In a loom-shuttle, in combination, the receiver for a wound yarn-load, a follower 125 movably mounted on said receiver, acting against the exterior of the said yarn-load and provided with a detent, and a trip adapted in its normal position to control the action of outside instrumentalities, and held by such 130 detent in an abnormal position until its release is permitted by depletion of the said yarn-load to the predetermined extent, substantially as described.

3. In a loom-shuttle, in combination, the shuttle-spindle, a follower acting against the exterior of the yarn-load applied to the shuttle-spindle, pivoted on said shuttle-spindle, 5 and provided with a detent, and a trip adapted in its normal position to control the action of outside instrumentalities, and held by such 10 detent in an abnormal position until its release is permitted by depletion of the said 15 yarn-load to the predetermined extent, substantially as described.

4. In a loom-shuttle, in combination, a movable follower provided with an adjustable contact acting against the exterior of the 15 wound yarn-load carried by the shuttle, and provided also with a detent, and a trip adapted in its normal position to control the action of outside instrumentalities, and held by such 20 detent in an abnormal position until its release is permitted by depletion of the said 25 yarn-load to the predetermined extent, substantially as described.

5. In a loom-shuttle, in combination, the shuttle-spindle, the follower carried by said

spindle and provided with an adjustable contact to bear against the exterior of the yarn-load upon the shuttle-spindle, and also with a detent, and the trip engaged by said detent to control the action of outside instrumentalities, substantially as described. 25

6. In a loom-shuttle, in combination, the shuttle-body, the shuttle-spindle, the follower moving in unison with said spindle, having also an independent indicating movement, and provided with a detent, and the trip mounted 30 upon the shuttle-body and engaged by said detent, one of the interengaging parts having the curved wing against which the other acts, to occasion automatic reengagement of the detent and trip as the spindle is lowered 35 into position in the shuttle-body, substantially as described. 40

In testimony whereof I affix my signature in presence of two witnesses.

HENRY BARDSLEY.
